Primary Examiner — Karen E Eldridge Powers

(57) **CLAIM**

I claim the ornamental design for a hoodie hat clip, as shown and described.

DESCRIPTION

FIG. 1 is a left side/top/rear perspective view of a hoodie hat clip showing my new design;

FIG. 2 is a right side/top/rear perspective view thereof;

FIG. 3 is a right side/bottom/rear perspective view thereof;

FIG. 4 is a rear elevation view thereof;

FIG. 5 is a top plan view thereof;

FIG. 6 is a right side elevation view thereof;

FIG. 7 is a bottom plan view thereof;

FIG. 8 is a front elevation view thereof;

FIG. 9 is a right side/top/front perspective view thereof;

FIG. 10 is a left side/top/front perspective view thereof; and,

FIG. 11 is a right side/bottom/front perspective view thereof;

1 Claim, 2 Drawing Sheets

FIG. 2

FIG. 1

FIG. 4

FIG. 3
